LENS GRINDING MACHINE

Lowell L. Houchin, Columbus, Ohio

Application March 1, 1935, Serial No. 8,903

12 Claims. (Cl. 51—119)

My invention relates to a lens grinding machine. It has to do, more particularly, with a lens grinding machine which is particularly suitable for grinding toric or cylindrical lenses but

5 which is also capable of use in grinding spherical lenses.

One of the objects of my invention is to provide a lens grinding machine of the type indicated which is of very simple construction and which 10 will operate in a very efficient manner.

Another object of my invention is to provide a lens grinding machine of such a nature that the grinding lines will be effectively broken up so that the lens produced will have a smooth surface and 15 polishing will be reduced to a minimum.

Another object of my invention is to provide a machine of the type indicated wherein all the necessary adjustments may be conveniently and quickly made.

20 Another object of my invention is to provide a lens grinding machine which is suitable for grinding lenses of any curvature and, particularly, for grinding lenses of strong plus curvature without buckling of the lens relative to the grinding 25 tool.

Another object of my invention is to provide a machine which has a minimum number of moving parts and which is so designed that friction and wear will be reduced to a minimum.

30 In its preferred form my invention contemplates the provision of a table which carries the lens grinding lap or tool. This table is so mounted that it will have a rotary motion, which may be easily varied, but it will not rotate about its 35 own axis. In other words, the table will move bodily in a rotary path in such a manner that any point on its surface shall describe a circle of the same diameter as that described by any other point on its surface and any straight line drawn

40 on its surface will move into successive positions which are parallel with each other. The lens is carried by a block which is mounted on a rocker arm that is reciprocated transversely in a straight line in order to cause the lens to move relative to 45

45 the lens grinding lap or tool which is carried by the table. Thus, the lens grinding lap or tool is caused to move in a rotary path and the lens is caused to move in a straight line transversely of the lens grinding lap. However, this straight 50 line movement is preferably at an angle relative to the axis of the lap or tool, as will be explained more in detail hereinafter. This combination of movements breaks up the lines so that a smooth

55 surface will be produced on the lens and polishing will be reduced to a minimum.

The preferred embodiment of my invention is illustrated in the accompanying drawings wherein similar characters of reference designate corresponding parts and wherein:

Figure 1 is a perspective view of a machine 5 made in accordance with my invention.

Figure 2 is a perspective view of the machine taken from a different angle than that of Figure 1.

Figure 3 is a detail in perspective of the mechanism for causing the lens carrier to reciprocate in a straight line transversely of the lap or tool carrier.

Figure 4 is a detail, in section, of the rocker arm which carries the lens carrier. 15

Figure 5 is a side elevation, partly broken away, of the machine.

Figure 6 is a plan view of the machine.

Figure 7 is a vertical section taken through the table or carrier which carries the lens grinding lap 20 or tool.

Figure 8 is a horizontal section taken substantially on line 8—8 of Figure 7.

Figure 9 is a view, more or less diagrammatic, illustrating how the straight line motion imparted 25 to the lens blank is at an angle relative to the axis of the tool or lap.

With reference to the drawings, I have illustrated my machine as comprising a base plate 1 upon which is mounted a pan 2. The pan and 30 base 1 have a central opening through which a vertical spindle or shaft 3 passes. This shaft or spindle 3 is suitably mounted for rotation, preferably in anti-friction bearings such as ball bearings. On the shaft 3 directly above the bottom 35 of the pan 2 is a cap 4 which prevents abrasive from reaching the bearings of shaft 3.

The shaft 3 is driven by a belt drive 5, as shown in the drawings, from a suitable source of power. Rotation of shaft 3 is controlled by a clutch of 40 a suitable type which is indicated generally by the numeral 6.

The spindle 3 is adapted to carry at its upper end a table or carrier upon which the lens grinding tool or lap is adapted to be mounted. As 45 shown best in Figure 7, the extreme upper end of the spindle 3 is positioned in the hub 7 formed on the lower surface of a disk or plate 8 and is suitably keyed therein. A second plate or disk 9 rests on the upper surface of the plate or disk 8. 50 This plate or disk 9 is held in position on the disk 8 by means of a pair of screw bolts 10 which depend from the plate or disk 9 and which pass through a pair of slots 11 formed in the disk 8. 55 The disk 9 may be adjusted concentrically or

eccentrically relative to the disk 8 and will be held in properly adjusted position if the bolts 10 are properly tightened.

The disk 9 carries the table or tool carrier 12. The table or tool carrier 12 is preferably of circular outline and has a depending stub shaft 3a disposed centrally thereof. This stub shaft 3a projects into a hub 13 formed eccentrically of the disk 9. A chamber is provided in the lower surface of the disk 9 and a ball bearing 14 is disposed therein in surrounding relation to the lower end of stub shaft 3a. A second ball bearing 15 is provided between the hub 13 and a depending shoulder 16 which extends from the lower surface of the table 12. These roller bearings serve to prevent tilting of the table 12 and to reduce friction to a minimum during rotary movement of the table 12. The table 12 has a depending skirt 17 adjacent its periphery which extends down in overlapping relation to the disk 9. This prevents abrasive from reaching the bearing 15.

It will be apparent that when the shaft 3 is rotated, the disk 8 and the disk 9 will also rotate therewith. Since the table 12 is mounted eccentrically on the disk 9, it will be moved bodily in a rotary path. When the disk 8 and disk 9 are in coincidence, as indicated in Figure 7, the table will move through its maximum rotary path. During this maximum rotary movement of the table, the weight of disks 8 and 9 will be equally distributed around the shaft 3. Thus, since there will be no unbalanced centrifugal force with relation to disks 8 and 9, vibration will be reduced to a minimum. The extent of the rotary movement of the table may be varied by adjusting disk 9 relative to disk 8 so that shaft 3a will move closer to shaft 3. However, I provide means to be subsequently described in detail for preventing the table 12 from rotating about its own axis. Because the shaft 3a is rotatably mounted in the member 9, rotation of member 9 and member 8 about the axis of shaft 3 is permitted, even though rotation of table 12 about its own axis is precluded.

Any tool suitable for grinding toric or cylindrical lenses may be mounted on the upper surface of the table 12. The means for readily mounting the tool or lap on the table 12 is illustrated best in Figure 1. It comprises a shoulder 18 near one side of the table against which the edge of a lens grinding lap or tool L abuts. This tool L will have any desired curvature or curvatures thereon depending upon the curvature or curvatures to be produced on the lens. Opposite the shoulder 18 is an upstanding lug 19 which is formed on the table. This lug 19 has a screw 20 threaded therethrough. A wedge member 21 of the shape shown is pivoted to lug 19, as at 22. When the screw 20 is threaded inwardly a sufficient distance its end contacts with the pivoted wedge member 21 and forces it downwardly between the lug 19 and the edge of the lap L. This forces the lap L firmly into contact with the shoulder 18. Thus, the lap may be readily mounted on the table 12 and will be tightly held in position thereon. To remove the lap from the table, it is merely necessary to loosen the screw 20. The lap L is mounted on the table 12 in such a manner that its longitudinal center line would be intersected by the axis of stub shaft 3a if it were continued.

Below the base 1, the shaft 3 has a pulley 23 (Figure 5) keyed thereon. Through the medium of a belt 24 this pulley 23 drives a pulley 25 which is keyed on the lower end of a shaft 26. This

shaft 26 is mounted in an upstanding vertically disposed housing 27. The shaft 26 is preferably mounted in ball bearings adjacent its upper and lower ends. The housing 27 is bolted or otherwise secured to the rear surface of an upstanding vertical support 28 which is secured to the base plate 1 adjacent its rear edge.

The vertically disposed support 28 has a yoke formed at its upper end. A housing 29 is positioned on the upper end of each arm of this yoke (Figure 3). Each housing 29 has a pair of spaced rollers 30 disposed therein. Each of these rollers has a continuous groove formed in its periphery. A shaft 31 has one end passing between one of the pair of rollers 30 and its opposite end passing between the other pair of rollers. The grooves in the rollers cooperate with the cylindrical surface of the shaft 31 to maintain it in position. However, the rollers are so arranged relative to the shaft 31 as to permit longitudinal reciprocation of the shaft.

The shaft 31 has a rocker arm 32 mounted thereon. This shaft 31 passes through a hub 33 formed intermediate of the front and rear ends of the rocker arm. The shaft is keyed in the hub 33 so that it will not rotate therein and so that the rocker arm may not slide along the shaft 31. However, the shaft is disposed between the rollers 30 in such a manner that it may rotate around its own axis in order to permit tilting of the rocker arm 32 about the axis of this shaft.

The rocker arm 32 is made in two sections as shown in Figures 4 and 5. One of these sections 34 is the section which has the hub 33 formed thereon. The other section 35 is connected thereto in the manner illustrated in Figure 4. Thus, the forward end of the section 34 is provided with a pair of spaced depending lugs 36. The rear end of the section 35 is provided with a socket formed by side walls and transverse walls 40. This socket receives lugs 36 which will be closely adjacent walls 37. Each lug 36 has a stub shaft 38 passed therethrough and the outer end of the stub shaft is disposed in a roller bearing 39 mounted in the wall 37 of section 35. Thus, the section 35 may rock relative to the section 34 and friction will be reduced to a minimum by the ball bearings 39.

I provide means for automatically taking up the wear of the roller bearings 39. This means 50 comprises an expansion spring 40 which has its rear end abutting the inner surface of the rear lug 36 and its forward end disposed in a socket member 41 formed on the rear end of stub shaft 38. This stub shaft 38 is normally held immovable in position by set screw 42a but when said screw is loosened it is free to slide in the opening in the forward lug 36. The other stub shaft 38 is held in position by a set screw 42. When the set screw 42a is loosened, the spring 40 will tend to move the forward stub shaft 38 in the direction of the arrow (Figure 4) which will also tend to move the section 35 of the rocker arm in the direction of the arrow. This will take up or compensate for wear of the forward roller bearing 39 and, since the rear stub shaft 38 is held in position by screw 42, will also take up or compensate for wear in the rear roller bearing 39.

The forward end of the section 35 of the rocker arm is inclined upwardly and outwardly as at 43 and then is continued horizontally outwardly as at 44 (Figures 1, 2 and 5). Thus, the forward portion 44 of the rocker arm is at a much higher level than the rear portion thereof. The forward end of the section 35 of the rocker arm car-

ries a block 45 which is adjustable thereon by means of a bolt 45a. This block 45 has a pair of depending pins 46. These pins fit into a pair of sockets formed in the upper surface of a lens blank holder H in such a manner that they may rock therein. The lens blank holder H may be of any suitable type and has a lens blank cemented to its lower surface. The extreme forward end of the section 35 of the rocker arm has a handle 47 formed thereon by means of which the rocker arm may be swung between inoperative and operative positions, as will be subsequently described.

The lens blank holder is carried by the rocker arm in such a manner that the lens blank will contact with the upper surface of the lap or tool L. The means for maintaining contact between the lens blank and lap with sufficient force to produce effective grinding comprises a thrust rod 48 which has its lower cone-shaped end (Figure 4) disposed in a socket 49, which is formed in the upper surface of section 35 of the rocker arm, in such a manner that it may rock therein. This rod 48 passes loosely upwardly through a sleeve 50 (Figures 1, 2 and 5) formed on the outer end of an arm 51. The arm 51 has a sleeve 52 at its rear end which fits over an upwardly projecting pin 53 that is supported on a member 28a which is mounted on the supporting structure 28. The arm 51 may be adjusted to any vertical or lateral position relative to pin 53 and may be held in adjusted position by a screw 54. The rod 48 has a head 55 on its upper end which will prevent it from passing downwardly through the sleeve 50. The rod is caused to exert a downward pressure on the rocker arm by means of expansion spring 56. This expansion spring 56 has its upper end abutting the lower end of sleeve 50 and its lower end abutting a collar 57.

It will be apparent that the spring 56 will press down and cause the rocker arm to force the lens blank into resilient but firm contact with the lens grinding lap. This pressure which maintains the lens blank and lap in contact may be varied readily by adjusting the arm 51 vertically on pin 53. The lower end of the rod 48 contacts with the section 35 of the rocker arm at the lowest point of the rocker arm. Thus, it will be apparent from Figure 1 that the force exerted by spring 56 is applied to the rocker arm at a point which is below the upper surface of the lens grinding lap. It is important to apply the pressure, which maintains the lap and lens blank in contact, at this low point on the rocker arm because this prevents buckling of the lens blank on the lap, especially when grinding strong plus lenses. Since the outer end of the rocker arm is higher than its rear portion, there is a downward pull exerted on the outer portion of the arm 51 tending to keep the lens blank and lap in contact, rather than a downward thrust. It is also important to have the spring 56 and rod 48 located at a point spaced rearwardly from the forward end of the rocker arm so as not to interfere with the operator when positioning the lens blank carrier or lap on the machine and with inspection during the grinding operation.

As previously stated, I provide means for causing the lens blank carrier to be reciprocated transversely in a straight line relative to the lap L which is mounted on the table 12. This means comprises a disk 58 (Figure 3) which is keyed on the upper end of a shaft 26 that is rotatably supported in the housing 27. This disk 58 has an undercut groove 59 in its upper surface. This

undercut groove 59 receives the head of a threaded bolt 60 which is held in adjusted position along the groove 59 by means of a nut 61 threaded thereon. This bolt 60 has an antifriction roller 62 mounted thereon. This roller 62 is disposed between the legs of the bifurcated rear end 63 of the rocker arm 32. The bolt 60 which carries the roller 62 may be adjusted along the groove 59 until it is eccentrically disposed relative to the disk 58. It may be held in any adjusted position. When it is eccentrically disposed and the shaft 26 and disk 58 are rotated, the rocker arm 32 will be moved laterally back and forth since longitudinal reciprocation of shaft 31 is permitted. This will cause the lens blank carrier to reciprocate in a straight line transversely of the lap L. During this lateral reciprocation of the rocker arm 32 the forward section 35 thereof may tilt or rock on the rear section 34. Consequently, the lens blank will always contact firmly with the lap L. The extent of the lateral reciprocation of the rocker arm 32 may be varied by varying the eccentric position of the bolt 60 and roller 62 relative to the disk 58.

In addition to the reciprocating motion imparted to the lens blank carrier, a rotary motion is imparted to the lap L by the mechanism shown in Figure 7 and previously described. However, as previously described, means is provided for preventing the table 12 and, consequently, the lens blank carrier reciprocates in a straight line and the lap L moves in a rotary path, the lens blank and lap will not rotate relative to each other and, consequently, the proper curve or curves will be imparted to the lens blank by the lap.

The means for preventing rotation of the table 12 about its axis and, consequently, rotation of the lens blank relative to the lap, will now be described. This means includes a pair of diametrically opposed lugs or projections 64 (Figures 2 and 6) which are formed integrally on the table 12. These lugs are in line with the longitudinal center line or axis of the lap L which is mounted on the table. The rear edge of each lug has a cup formed therein which receives a point formed on the forward end of a thrust rod 65. The rear end of this thrust rod also has a point formed thereon which fits into a cup bearing formed on the lower end of a substantially semicircular arm 66. The upper end of the arm 66 has a split collar 67 which fits around one end of a shaft 68 that has its opposite ends rotatably mounted in bearings 69 which are supported on the housings 29 at opposite sides of the machine. It will be apparent that one of these members 66 is secured to each end of shaft 68. The pointed ends of each rod are held in the cups by means of a tension spring 70. One end of the tension spring is hooked over a hook 71 connected to the lug 64. The opposite end is connected by a hook 72 to the lower end of the arm 66. In the initial adjustment of the machine the bolts 67a may be loosened to permit adjustment of the arms 66 on the shaft 68.

The rods 65 and arms 66 will permit the table 12 to move bodily in a rotary path but will prevent it from rotating about its own axis. Thus, the lap will be prevented from rotating relative to the

lens blank. Consequently, the curves on the lap will be imparted to the lens blank. The rods 65 are stiff enough to keep from bending during operation of the machine. Each end of each rod 65 is free to rock in the cup bearing. Consequently, the rotary motion of the table will be permitted without bending the rods 65 and with a minimum amount of friction being generated. Because the rods 65 do not bend during rotary movement of the table, the lens blank will always be accurately held in its proper position relative to the lens grinding lap.

As shown in Figures 6 and 9, one of the rods 65 is slightly longer than the other. Thus the diameter line A—A which passes through the center of lugs 64 is at an angle to the shaft 31. In positioning the lap L and the lens blank B on the machine, the axis of the blank and the axis of the lap are brought into coincidence and these axes will lie along the line A—A. However, the direction of the straight line reciprocation of the lens blank will be in the direction of the straight line D—D which is at an angle to the axis of the lens blank and lap and at an angle to the line A—A. Thus, although rods 65 will function to maintain the axis of the lens blank parallel to the axis of the lap at all times during the rotary movement of the table, the straight line motion of the blank will be at an angle to the axis of the lap.

I have found that it is important to have this straight line reciprocation of the blank at an angle relative to the axis of the lap. During the grinding of the lens blank, the blank moves into overlapping relation with the edge of the lap. If the straight line reciprocation is parallel to the axis of the lap, I have found that waves may be produced in the lens blank but if the straight line reciprocation is at an angle to the axis of the lap, the production of these waves is obviated.

The member 28a which carries the mechanism for exerting a downward force on the rocker arm 32, is free to rock around the shaft 68. However, rocking of this member 28a is normally prevented by a latch member 73 (Figures 1 and 2). This latch member 73 is of arcuate form and is pivotally mounted on the member 28a. It has a depending lug 74 which normally is dropped down in front of a plate 75 which is rigidly carried by the supporting structure 28. The spring 56 exerting pressure against the rocker arm will tend to cause the arm 51 to swing upwardly and, consequently, the member 28a to rock about its pivots. However, since the lug 74 is in engagement with the forward edge of plate 75, this will be prevented and, consequently, the spring 56 will force the rocker arm 32 downwardly.

However, when it is desired to replace a lens blank or lap, the latch 73 is disengaged from the plate 75. This will permit the member 28a to rock about its pivot points and the arm 51 to swing upwardly. A spring 76 is connected to the structure 28a which normally tends to cause the member 28a to rock rearwardly. Consequently, when the latch 73 is released, the structure 28a and associated parts will automatically rock rearwardly. Disengagement of the latch 73 and plate 75 is facilitated by pressing downwardly on a handle structure 51a on the outer end of arm 51. Thus, when the latch is released, the pressure on the rocker arm 32 will also be released.

In order to cause the rocker arm to swing

rearwardly with the arm 51, I provide a flexible strap 77. This strap 77 has its upper end connected to an arm 78 that is mounted on the vertically disposed pin 53 carried by member 28a. The lower end of this strap 77 is connected to the rocker arm 32 as at 79. This strap is of such a length that when structure 28a rocks rearwardly the rocker arm will also be swung upwardly. The structure 28a and associated parts will swing rearwardly until the lug 74 of latch 73 drops behind the rear edge of plate 75 and the latch member will keep it in its rearwardmost position until disengaged. When the member 28a rocks rearwardly the rocker arm 32 will also be swung upwardly as explained through the medium of the strap connection 77. However, upward swinging movement of the rocker arm 32 will be limited by contact of its rear end with the disk 58.

In the operation of this machine, the lens blank and the lap are properly positioned on the machine in the manner previously described. The lap mounted on the machine will be of the proper curve or curves depending upon the curve or curves to be imparted to the lens blank. It may be either toric or cylindrical. The axis or longitudinal center line of the tool or lap is properly lined up relative to the axis or longitudinal center line of the lens blank carrier. The table 12 is adjusted eccentrically of the shaft 30. The roller 62 is adjusted eccentrically of the disk 58. The spring 56 and associated parts are adjusted to place the proper downward pressure on the rocker arm 32. Then the machine is started in operation.

The table 12 will be caused to travel bodily in a rotary path but it will be prevented from rotating about its axis and, consequently, the lap will be prevented from rotating relative to the lens blank. The rocker arm 32 will be moved in a straight line laterally back and forth but in a direction at an angle to the axes of the blank and lap. Since the outer portion of the arm is free to rock, the lens blank and tool or lap will always be in firm engagement with each other. This combination of motions will serve to effectively break up the grinding lines so that the lens produced will be very smooth and polishing will be reduced to a minimum.

The rotary motion of the table may be readily varied as previously explained. The lateral reciprocatory movement of the rocker arm may also be readily varied. Also, the downward pressure on the rocker arm may be varied. Consequently, the machine may be readily adjusted for grinding any type of lenses.

It will be apparent from the above description that I have provided a machine for grinding lenses having many desirable features. The machine is of very simple construction and will operate in a very efficient manner. The combination of motions in the machine results in effectively breaking up the grinding lines so that the lens produced will have a smooth surface and polishing will be reduced to a minimum. This machine is suitable for grinding lenses of any curvature and operates without difficulty even on strong plus lenses. The machine is designed so that it has a minimum number of moving parts and friction and wear is reduced to a minimum.

It will be apparent that the movements of the lap and lens carrier could be reversed. That is, the rotary movement could be imparted to the lens blank carrier and the reciprocating move-

ment to the tool carrier. In the claims where I state that the tool or lap carrier rotates bodily about an axis and the lens blank carrier reciprocates in a straight line, I also intend to cover 5 the reverse of this.

When I use the term "grinding" in the specification and claims, I also intend to cover polishing and other similar operations.

Having thus described my invention, what I 10 claim is:

1. A lens grinding machine comprising a supporting structure, a rotatable spindle, a lap carrier mounted eccentrically on said rotating spindle and pivotally connected thereto, means for 15 preventing rotation of said lap carrier about its own axis during rotation of said spindle, a rocker arm supported on said supporting structure and extending over said lap carrier, said arm comprising two sections one of which may rock on 20 the other, a lens blank carrier carried by one of the sections of said rocker arm, said rocker arm having its inner end mounted on a shaft, means for moving said shaft longitudinally of itself to cause lateral reciprocation of the rocker arm, said rocker arm being 25 mounted in such a manner as to permit vertical movement thereof, and resilient means for exerting a downward force on said rocker arm.

2. A lens grinding machine comprising a supporting structure, a rotatable spindle carried by said supporting structure, a lap carrier pivotally carried by said rotating spindle and being adjustable eccentrically of said spindle, means for preventing rotation of said lap carrier about its 30 axis during rotation of said spindle, a rocker arm supported on said supporting structure and extending over said lap carrier, said arm comprising two sections one of which may rock on the other, a lens blank carrier carried by one of the sections of said rocker arm, said rocker arm having its inner end keyed to a shaft which is free to rotate, means for moving said shaft longitudinally of itself to cause lateral reciprocation of the rocker arm, said means comprising 35 an eccentric operatively connected to said arm, and resilient means for exerting a downward force on said arm.

3. In a lens grinding machine, a lap carrier, means for mounting a lap on said carrier, said 40 means comprising a shoulder on said carrier with which one edge of said lap will engage, a lug opposite said shoulder having a screw threaded therein, a wedge member pivoted to said lug at the inner side thereof, the inner end of said screw 45 engaging said wedge member and being operable to force the wedge member between said lug and the edge of the lap and to force the opposite edge firmly into contact with said shoulder.

4. A lens grinding machine comprising a lap carrier adapted to have a lap mounted thereon, means for moving said lap carrier in a rotary path, a lens blank carrier adapted to have a lens blank mounted thereon, means for preventing rotation of said lap carrier about its axis during 50 the rotary movement thereof in order to maintain the axis of the lap and the axis of the lens blank in coincidence or parallel to each other at all times, and means for causing said lens blank carrier to move in a straight line which is at an angle to the axis of the lap.

5. A lens grinding machine comprising a lap carrier adapted to have a lap mounted thereon, means for moving said lap carrier in a rotary path, a lens blank carrier adapted to have a lens blank mounted thereon, means for prevent-

ing rotation of said lap carrier about its axis during the rotary movement thereof in order to maintain the axis of the lap and the axis of the lens blank in coincidence or parallel to each other at all times, said means including a pair of rods having one of their ends connected to said lap carrier at diametrically opposed points and their opposite ends connected to a stationary support, and means for causing said lens blank carrier to move in a straight line, one of said rods being shorter than the other so that the straight line motion of the lens blank carrier will be at an angle to a line extending through the points of connection of the rods to the lap carrier.

6. A lens grinding machine comprising a supporting structure, a rotatable spindle carried by said supporting structure, a lap carrier pivotally carried by said rotatable spindle, means for preventing rotation of said lap carrier about its axis 20 during rotation of said spindle, a rocker arm supported on said supporting structure and extending over said lap carrier, said arm comprising two sections, one of which may rock on the other about its own axis, a lens blank carrier 25 carried by one of the sections of said rocker arm, said rocker arm having its inner end mounted on a shaft, and means for moving said shaft longitudinally of itself to cause lateral reciprocation of the rocker arm, said rocker arm being 30 mounted in such a manner as to permit vertical movement thereof.

7. A lens grinding machine comprising a supporting structure, a rotatable spindle carried by said supporting structure, a lap carrier pivotally 35 carried by said rotatable spindle, means for preventing rotation of said lap carrier about its own axis during rotation of said spindle, an arm supported on said supporting structure and extending over said lap carrier, a lens blank carrier carried by said arm, said arm having its inner end mounted on a shaft, and means for moving said shaft longitudinally of itself to cause lateral reciprocation of the arm, said arm being mounted in such a manner as to permit vertical move- 40 45 ment thereof.

8. A lens grinding machine comprising a supporting structure, a lap carrier mounted on said supporting structure, means for moving said carrier bodily in a closed path, an arm supported 50 on said supporting structure and extending over said lap carrier, a lens blank carrier carried by said arm, said arm having its inner end mounted on a shaft, and means for moving said shaft longitudinally of itself to cause lateral reciprocation 55 of the arm, said arm being mounted in such a manner as to permit vertical movement thereof.

9. In a lens grinding machine, a supporting structure, a rotatable spindle, a table mounted on said spindle and being pivotally connected 60 thereto, means for preventing rotation of said table about its own axis during rotation of said spindle, said means comprising a pair of rods, said rods having one of their ends freely disposed in sockets at diametrically opposed points 65 on said table, the opposite ends of said rods being freely disposed in sockets formed in a pair of arm members, both of said arm members being connected to a single member rotatably mounted on a stationary structure, and resilient 70 means for normally maintaining the ends of the rods in said sockets.

10. In a lens grinding machine, a supporting structure, a rotatable spindle, a table mounted on said spindle and being pivotally connected 75

thereto, means for preventing rotation of said table about its own axis during rotation of said spindle, said means comprising a pair of rods, said rods having one of their ends connected to said table at diametrically opposed points, the opposite ends of said rods being connected to a pair of arms, said arms being carried by a single member mounted for rotation on a stationary structure, a lens blank carrier mounted on said supporting structure, means for moving said carrier in a straight line, said rods being of such lengths and so disposed that the straight line movement of said lens blank carrier will be at an angle to a line passing through the diametrically opposed points at which said rods are connected to said table.

11. A lens grinding machine comprising a supporting structure, a rotatable spindle carried by said supporting structure, a lap carrier pivotally carried by said rotatable spindle, means for preventing rotation of said lap carrier about its axis during rotation of said spindle, said means comprising a pair of rods, said rods having one of their ends connected to said table at diametrically opposed points, the opposite ends of said rods being connected to a pair of levers, said levers being carried by a single member mounted for rotation on said supporting structure, an arm

supported on said supporting structure and extending over said lap carrier, a lens blank carrier carried by said arm, said arm having its inner end mounted on a shaft, and means for moving said shaft longitudinally of itself to cause lateral reciprocation of the arm, said rods being of such lengths and so disposed that a line passing through the diametrically opposed points at which said rods are connected to said lap carrier will be at an angle to said shaft.

12. In a lens grinding machine, a supporting structure, a lap carrier mounted on said supporting structure, means for moving said carrier bodily in a closed path, an arm supported on said supporting structure and extending over said lap carrier, said arm comprising a forward portion disposed at a higher level than the rear portion thereof, a lens blank carrier carried by the forward portion of said arm, the rear portion of said arm lying substantially in the same plane as said lap carrier, said arm being mounted for vertical movement, and a thrust member for exerting a downward force on said arm, said thrust member applying the force on the rear portion of the arm at a point substantially level with the lap carrier.
